UNITED STATES PATENT OFFICE.

DAVID H. DARRIN, OF CRANFORD, NEW JERSEY, AND EMBURY McLEAN,
OF BROOKLYN, NEW YORK; SAID DARRIN ASSIGNOR TO SAID McLEAN.

AUTOMATIC HEAT-CONTROLLER FOR STEAM-BOILER FURNACES.

SPECIFICATION forming part of Letters Patent No. 690,931, dated January 14, 1902.

Application filed January 8, 1898. Serial No. 666,108. (No model.)

To all whom it may concern:

Be it known that we, DAVID H. DARRIN, of Cranford, Union county, New Jersey, and EMBURY McLEAN, of Brooklyn, borough of 5 Kings, New York, have invented certain new and useful Improvements in Automatic Heat-Controllers for Steam-Boiler Furnaces Supplied with Forced-Air Draft, of which the following is a specification.

10 This invention has for its object to increase the efficiency of forced-air-draft apparatus and improve the results of heating-furnaces provided with such apparatus; and to this end the invention contemplates a special organization of apparatus hereinafter set forth for effecting simultaneous regulation of the forced-air supply and of the discharge of the gaseous products of combustion through the stack or flue of the furnace, 15 thereby causing to be maintained in the furnace a practically-uniform pressure under all conditions of the rate of combustion of the fuel and the consequent retention of the heated gases in the furnace or boiler setting 20 and the prevention of uncalled-for air entering the furnace, thus insuring the most economical results from the burning of such fuel.

Heretofore forced-air-supplying apparatus 30 for furnaces of boilers, &c., have been devised in one class of which the blast of air has been regulated by the steam from the boiler heated by the furnace acting through a controlling device to regulate the supply of 35 the active agent actuating the motor which operates the fan or blower, the various devices constituting the apparatus being so arranged and operated that the fan or blower does not entirely cease operating when the 40 maximum pressure in the boiler is reached, but at such times supplies sufficient air to the furnace beneath the grate-bars as will prevent undue burning away of the grate-bars and to keep the fuel alight. While the 45 use of such apparatus produces good results, yet the best results are far from being attained, for the reason that when the fan is supplying the minimum amount of air to the furnace the natural draft of the stack causes an 50 attenuation of the gases in the furnace above the fuel, thus increasing their flow and to a

considerable extent drawing in cold air above the fuel, which chills the products of combustion, contracts the plates and tubes, and cools the boiler and setting. It is also common practice to automatically regulate the stack or flue opening by damper-regulators controlled by the pressure of the steam in the boiler, and special regulators have been devised actuated by fluid-pressure from an independent source in such manner as to positively act on the motor device of the controller to close it and to release the same to allow the controller to open by a free discharge of the fluid from such motor device. 55

Now in carrying out the invention we employ a forced - air - draft apparatus and a damper - controlling device having the general characteristics above set forth, combining the two in such manner and simultaneously regulating or controlling them through the medium of a fluid under pressure supplied from an independent source, so as to cause a closing of the damper in the flue or stack at the same time and in conformity 70 with the reduction of air supplied to the furnace by the forced - draft apparatus, thus confining the hot gases in the furnace or boiler setting and maintaining a substantially uniform pressure therein and preventing 75 air being drawn into the furnace above the fuel in excess of that properly delivered below the fuel by the fan at its lower speed, as would occur if the stack were left fully open for its normal natural draft to act. 80

To more fully describe the invention, reference will now be had to the accompanying drawings, forming part of this specification, in which—

Figure 1 is a view showing all of the apparatus and devices suitable for the practical carrying out of the invention conventionally arranged to more clearly show their relation to one another. Fig. 2 is an enlarged view showing the controlling devices in section; 90 Fig. 3, a vertical section of the controlling-medium regulator or governor; Fig. 3^a, a section therethrough on the line 3 3 of Fig. 3, and Fig. 4 a front view of the governor I with the front plate removed. 95

The general features of the invention, without going into details of construction of the 100

various parts and devices, will be first described by reference to Fig. 1, which illustrates the application of the invention to a steam-boiler and its furnace. The air for the combustion of the fuel in the furnace is supplied by the blower A, through the conduit A', to the ash-pit or under side of the furnace B, all parts of which are properly closed to exclude the entrance of air excepting that supplied by the blower. A damper A² is shown at the mouth of the conduit A', arranged so as to deflect the air and distribute it to all parts of the grate-bars. The boiler B' and smoke-stack B² are of the ordinary construction. The main steam-pipe B³ supplies steam through the pipe C to the motor C', connected to the blower A, to produce the forced-air draft. This pipe C is provided with a pressure-regulator or reducing-valve D, set to impose to the motor C' the desired speed to provide a maximum amount of air to the furnace B, and it is also provided with the controller E, actuated to entirely cut off the steam passing through the pipe C when the normal working pressure of the steam in the boiler is exceeded; but at such times sufficient steam passes to the motor C' to maintain it in motion and keep up a small supply of air to the furnace through the by-pass pipe C², which is provided with a pressure-regulator or reducing-valve F, which allows just enough steam to pass to the motor C' to keep it uniformly moving at its reduced speed.

The damper G in smoke-stack B² is connected by the levers G' to the damper-controller H, which when positively actuated by the fluid-controlling medium tends to close the damper against the action of the weight G², which tends to open the damper.

The regulator or governor I of the fluid-controlling medium is at its lower end connected by the pipe I' to the steam-space of the boiler B' at I². The upper end of this governor I connects with the source of the controlling fluid-pressure by the pipe J, which source is here represented as an air-compressor J', operated to supply and maintain a charge of compressed air in the reservoir J². A pipe K, extending from the upper part of governor I, connects with and is common to both the forced-air-draft-motor controller E and the damper-controller H.

As the details of construction of the various devices so far here described form no part of the invention, we will, before entering into such details, briefly state the functions of the different devices in setting forth their coöperation to produce the desirable results sought by the invention. Now assuming that the forced-air-draft motor C' has been running at its maximum speed, steam being supplied thereto mainly through the pipe C, and that the steam in the boiler has slightly exceeded its normal working or attained its maximum pressure, the steam at such increased pressure will by the pipe I' act on the governor I and allow air to flow between the pipes J and

K from the reservoir J², said air by its pressure thus simultaneously operating the controller E of the air-draft motor C' to cut off the main supply of steam to said motor and the consequent main supply of air to the furnace and the damper-controller H to close the damper G, as shown in the drawings, to such an extent as will prevent the escape of the heated gases from the furnace and boiler setting beyond what is necessary to maintain the normal and uniform pressure in the furnace now being supplied with the greatly-reduced volume of air. As soon as the steam falls to its normal working pressure it ceases to operatively act on the governor I, communication between the pipes J and K being now closed and the pipe K vented or opened to the atmosphere, thereby releasing the controllers E and H from the controlling fluid-pressure and again permitting the full working quantity of steam to pass to the motor C' and the weight G' to again open the damper G. The venting of the pipe K may be such as to allow the compressed air to escape slowly from the controllers E and H, so that the speed of the motor C' is gradually increased and the damper G gradually opened, while their reverse actions, due to increase of pressure in the boiler through the operation of the governor I, are much quicker.

To more fully explain the construction and operation of the various devices employed in this combined forced-air-draft and damper regulator, such suitable devices are illustrated on an enlarged scale and in section at Figs. 2 and 3. The regulator or governor of the controlling medium comprises a chamber L, in communication with the boiler by the pipe I' and covered by a flexible diaphragm L², against which bears a lever L', pressed against the diaphragm by an adjustable spring L³; another chamber M in communication with the controlling air-supply pipe J through a fine orifice M³ and having an outlet M⁴ somewhat larger than the inlet-orifice; a diaphragm M', closing this chamber; a spring-actuated lever M², provided with a valve-seat to close the outlet-orifice M⁴ of the chamber M; a pivoted arm N, connected to the diaphragm M'; a supply and vent valve O, actuated by a lever N', carried by the arm N, so as to close communication between the air-pipes J and K by seating against the valve-seat O' and to close the air-vent of the pipe K, which is around the free-fitting stem of the valve, by seating against the valve-seat O² when it moves away from the seat O', as shown at Fig. 2. The free end of the arm N has a projection N², straddling a post N³, projecting laterally from the side of the casing and provided with two adjustable stop-nuts, between which the projection N² plays, whereby the extent of movement in either direction of the arm N and diaphragm M' is determined. The lever N', carried by the arm N, is a spring-actuated toggle-lever and is pivoted near its upper end to the arm N and has its lower end connected

with that arm by a slot-and-pin connection N⁴. The extreme upper end of lever N' works in a groove in the stem of the valve O. The tension of the spring L³, bearing on the lever 5 L', operated by the diaphragm L, is adjusted by a screw L⁴, passing through the center of dial L⁵ and provided with an index-pointer L⁶ and a thumb-piece L⁷.

The two regulating or reduction valves D 10 and F are of the ordinary construction, and their functions in the steam-pipe C and bypass C² will be readily understood from the foregoing statement. The same may be said of the controllers E and H, they being ordinary diaphragm fluid-motors, the diaphragm 15 of the controller E being attached to the valve E' in such manner as to close it when the diaphragm is inflated, said valve being opened by the spring E² when the controller 20 is relieved of the air-pressure. The diaphragm H' of the controller H is connected to the damper G through the system of levers G' in such manner that its inflation tends to close the damper against the opening action of 25 the weight G². The diaphragms of these controllers E and H are shown inflated at Fig. 2, the parts of the governor I being shown at Fig. 3 in position assumed by them after the boiler-pressure has fallen sufficiently for the spring- 30 actuated lever L' to recede from the lever M², which now closes the discharge or vent orifice M⁴ of the chamber M, allowing air from the pipe J to accumulate in the chamber M to force the diaphragm M' outwardly, and so 35 close the valve O onto the seat O' and open the vent around its stem by leaving the seat O². The air or controlling medium is thus cut off from the controllers E and H, and the air that is in these controllers is now free to 40 gradually escape by the vent around the stem of the valve O. In this operation the parts effect the movement of the valve O in the following manner: The pressure under the diaphragm M moves the arm outwardly, and 45 the upper end of toggle-lever N' being held against movement by the stem of valve O, which now bears on its seat O², the joint in the toggle-lever is moved beyond its center line, and its spring then acts to instantly 50 move the lever into the position shown in Fig. 3, there transferring the valve O from the seat O² to the seat O'. The reverse of this operation occurs, when the pressure under diaphragm M is relieved by the opening 55 of the vent M⁴. When the steam again rises sufficiently to force out the lever L', the seat on the lever M² is moved away from the discharge-orifice of the chamber M, allowing the

air to escape therefrom faster than it enters therein through the smaller inlet-orifice. The 60 diaphragm then collapsing causes the valve to close the vent around its stem and allows air to pass from the pipe J to the controllers E and H through the pipe K, as shown at Fig. 3. 65

y in Fig. 3 indicates an aperture in the casing constituting a vent for the compressed air that may be discharged within the casing.

Other forms of controllers and governing devices than those here shown may be used, 70 and also any source of fluid-pressure other than that illustrated at J' J² may be utilized as the controlling medium to produce the desired result of the invention, so we do not limit ourselves to the combination of the particular 75 devices here shown.

We claim as our invention--

1. An automatic apparatus for controlling the heat of a steam-boiler furnace, consisting of a blower for supplying a forced-air draft 80 to the furnace, a motor for operating the blower, a damper in the flue or stack, two controllers for regulating respectively the forced-draft motor and the damper, and a single regulator or governor actuated by steam from 85 the boiler to simultaneously set in action the forced-draft motor and damper controllers, when the pressure in the boiler rises to close the damper and check the blower-motor, and when the pressure falls to open the damper 90 and permit the blower-motor to resume its normal speed.

2. An automatic apparatus for controlling the heat of a steam-boiler furnace, consisting of a blower for supplying a forced-air draft 95 to the furnace, a motor for operating the blower, a damper in the flue or stack, two controllers for regulating respectively the forced-draft motor and the damper, a fluid-controlling medium from an independent 100 source for actuating the controllers, and a single regulator or governor actuated by steam from the boiler to permit said fluid medium to simultaneously cause the action of said controllers, whereby when the boiler-pressure 105 rises the damper is closed and the blower-motor checked, and when the pressure falls the damper is opened and the blower-motor permitted to resume its normal speed.

In testimony whereof we have hereunto 110 subscribed our names.
